Des. 181,499
Patented Nov. 19, 1957

181,499

WASHING MACHINE AGITATOR

Thomas R. Smith and Charles W. Burkland, Newton,
Iowa, assignors to The Maytag Company, Newton,
Iowa, a corporation of Delaware

Application February 4, 1957, Serial No. 44,750

Term of patent 14 years

(Cl. D49—1)

Figure 1 is a side elevational view of a washing machine agitator showing our new design;

Figure 2 is a top plan view of the agitator shown in Figure 1; and,

Figure 3 is an elevational end view of the agitator shown in Figure 1.

We claim:

The ornamental design for a washing machine agitator, as shown.
